AUTOMATIC CYLINDER TRACKING APPARATUS

Emilio G. Mastroianni, Endicott, N.Y., assignor to General Aniline & Film Corporation, New York, N.Y., a corporation of Delaware

Filed Feb. 18, 1963, Ser. No. 259,102

4 Claims. (Cl. 95—77.5)

This invention relates to improvements in automatic cylinder tracking mechanisms, particularly adaptable to the exposing or printing cylinder of a diazotype printing and developing apparatus.

Diazotype photocopying machines are widely employed in industry for making exact duplicates of translucent originals, such as drawings or letters, delivering a positive copy which can be immediately used without further processing or drying. For this reason, these machines are generally termed "dry printing and developing machines," to distinguish them from other types in which the exposed material is liquid developed and thereafter must be dried before it can be used.

Diazotype machines have generally three functional component assemblies combined into one operating unit. The first assembly, designated as a printer, generally includes a transparent rotating cylinder enclosing a source of high-intensity mercury arc light. The sensitized material, in contact with the original, is fed around the surface of the cylinder to be exposed to the high-intensity light. The second assembly is a separator conveyor unit for separating the original from the sensitized material and conveying the sensitized material to a developer; and the third assembly is a developer unit where the exposed, sensitized material is subjected to the vapors of a volatile developing agent, such as aqueous ammonia, and thereafter delivered to a receiving tray.

In the printing unit to which this invention is directed, the rotating cylinder is generally supported upon fixed rollers which function as bearings. In the larger machines, this construction has caused a considerable problem due to the fact that the cylinder will tend to creep laterally as it is rotated. This lateral movement can cause chipping of the edges of the cylinder or breakage thereof. Accordingly, it is a primary object of this invention to provide an improved automatic cylinder tracking mechanism, including a cylinder support arrangement which senses any creep of the cylinder and corrects the track by displacement of the cylinder automatically in the opposite direction, thus keeping the cylinder centered between its support bearings.

A particular feature of this invention is that the cylinder support rollers or bearings are carried by a pivotable caster arm which, in turn, is moved in response to a thrust bearing that senses axial displacement of the cylinder to cause tracking of the cylinder in the opposite direction.

Other objects and features will be apparent from the following description of the invention, pointed out in particularity in the appended claims and taken in connection with the accompanying drawings in which:

FIG. 1 is a side view illustrating the automatic cylinder tracking mechanism of this invention at both ends of the rotatable cylinder; and

FIG. 2 is a perspective view further illustrating the component parts of one of the automatic tracking units.

During the exposing or printing operation, the sensitized material in contact with an original is fed around the periphery of a rotating cylinder which contains a high-intensity light source. As mentioned before, during rotation, the cylinder tends to creep laterally or horizontally. If means are not present to prevent this creep, the edges of the cylinder are likely to chip and break and other

2

disadvantages ensue. This invention provides a unique mounting arrangement for supporting the printing cylinder on a pair of roller supports or bearings which are mounted on a pivotable caster arm and this arm, in turn, is controlled in its pivotal movement by an end thrust bearing which senses any lateral creep of the cylinder and positions the support rollers or bearings so as to track the cylinder in the opposite direction. There are two such automatic tracking units, one at each end of the cylinder and they are appropriately interconnected so that the cylinder is always effectively centered.

Referring now to the drawings, the cylinder 10 is constructed of glass and usually contains a high-intensity light source therein (not shown). An original and sensitized sheet are fed in contact with each other by means of belts 12 around a portion of the cylinder 10. The friction of the moving belts 12 also rotates the cylinder 10.

At each end of the cylinder 10, there is an automatic tracking unit 14 and 14'. Since each of these units and each of the components therein are identical at each end of the cylinder, only one of the units will be described in detail and the corresponding unit at the opposite end of the cylinder will be designated by the identical reference numerals bearing primary indices.

The tracking mechanism 14 is mounted on a support which may be a casting having a flange 20 and a cylindrical collar portion 22. It is attached to end plate 16. A stepped cutout 24 is provided in the collar portion 22 and an integrally cast yoke support 26 is provided at the bottom of the collar portion 22.

The yoke support 26 rotatably carries a bifurcated caster arm 28 for pivotal movement about the axis 30. The cylinder 10 has a collar 32 at the end thereof which is supported by a pair of rollers 34 and 35, rotatably mounted on stub shafts 36 which, in turn, are carried by the ends 38 of the caster arm 28.

An end thrust roller 40 is positioned to contact the edge of the collar 32 and is, therefore, mounted in a plane substantially perpendicular to the mounting of the support roller 34. The end thrust roller 40 is rotatably mounted on a shaft in the arm 42 rigidly secured to the caster arm 28 by a securing nut 44.

A bracket 46 is secured to the end 38 of the caster arm 28 and is connected to a tension spring 50 which, in turn, is connected to a cable 51. The cable 51 interconnects the two automatic tracking units for substantially simultaneous movement.

The operation of the invention will now be described. The cylinder 10, having end collars 32 and 32', is rotated by means of the belts 12. The collars 32 and 32' rest upon rollers 34, 34' and 35, 35'. These rollers, in turn, are mounted on caster arms 28 and 28' so that they can be displaced for the purpose of cylinder tracking.

As the cylinder 10 is rotating, it has a tendency to creep laterally. The arrangement of this invention keeps the cylinder within a confined area and opposes the tendency toward lateral creep. The thrust bearings 40 and 40' contact the ends of the cylinder 10 and any lateral movement of the cylinder causes the thrust bearings 40 and 40' to pivot the caster arms 28. Pivotal movement of caster arms 28 moves the rollers 34 and 35 so as to counteract the lateral shift of the cylinder 10. For example, if the cylinder 10 tends to creep toward the right, then the rollers 34 and 35 would be displaced by a slight turning of the arm 28 around the pivotal axis 30. Due to the interconnection of units 14 and 14' by means of the cable 51, the rollers 34' and 35' will partake in similar compatible movement causing a shift of the cylinder in the same direction. In a similar manner, but in an opposite sense, if the cylinder 10 tends to creep toward the left, the opposite result will be obtained.

Although the automatic tracking arrangement of this invention utilizing a caster effect and a sensing end thrust roller is especially applicable to printing cylinders of diazotype printing machines, it will be apparent to those skilled in the art that other rotatable cylinders could be similarly tracked automatically.

What is claimed is:

1. An automatic cylinder tracking apparatus which comprises:
  - (a) bearing means for rotatably supporting the cylinder,
  - (b) caster arms carrying the rotatable support bearing means,
  - (c) a stationary support means for pivotally supporting the caster arms, and
  - (d) an end thrust sensing means connected to the caster arms and adapted to contact the cylinder and sense lateral displacement thereof, so that any lateral creep of the rotating cylinder which is sensed by the end thrust sensing means, will be transmitted to the caster arm which, in turn, positions the rotatable support bearings for tracking the cylinder in a direction opposite to the direction of lateral creep.
2. An apparatus for keeping a rotating cylinder substantially centered within rotatable bearing rollers supporting the cylinder at opposite ends thereof, which comprises:
  - (a) a stationary support adjacent each end of the rotatable cylinder,
  - (b) a bifurcated caster arm pivotally mounted on the stationary support adjacent each end of the cylinder, the caster arm carrying the rotatable bearing rollers for rotatably supporting the cylinder,
  - (c) an end thrust roller at each end of the cylinder,
  - (d) means supporting the end thrust rollers from the caster arm, the end thrust rollers adapted to contact the ends of the cylinder and sense lateral movement and transmit the sensed movement through the sup-

porting means to the caster arms, the caster arms being pivotable to move the rotatable bearing rollers and to thereby track the cylinder in a direction opposite to the direction of lateral movement.

3. An apparatus as defined in claim 2 further comprising resilient means connecting each of the bifurcated caster arms for substantially simultaneous movement.

4. In combination with a printing and exposing unit of a diazotype copy machine including a glass printing cylinder with end collars, belts contacting the periphery of the cylinder for rotating the same, an improved cylinder tracking apparatus comprising:

- (a) a stationary support adjacent each end of the rotatable cylinder and at least partially enclosing the end collars thereof,
- (b) a bifurcated caster arm pivotally mounted by the stationary support, there being a caster arm for each end of the cylinder,
- (c) rotatable bearing rollers for contacting the collars of the glass cylinder and rotatably supporting the cylinder,
- (d) means mounting the bearing rollers to each end of each of the bifurcated caster arms,
- (e) a pair of end thrust rollers, each adapted to contact an opposite end of the cylinder,
- (f) means for supporting the end thrust rollers from the caster arm such that movement of the cylinder against the end thrust rollers causes corresponding movement of the caster arm, and
- (g) resilient means including a cable and tension springs interconnecting the bifurcated caster arms for substantially simultaneous movement so that any sensed lateral creep of the cylinder will result in repositioning the pivotable caster arms and rotatable supports carried thereby to cause the cylinder to track in a direction opposite to the creep.
